FURNACE CONTROL SYSTEM

George W. Bailey, Cortland, N. Y.

Application April 11, 1932, Serial No. 604,458

14 Claims. (Cl. 236—11)

My invention broadly relates to novel air-flow controls and more specifically pertains to coordinated temperature responsive devices for furnaces capable of effecting completely automatic temperature regulation and which devices include a thermostatic switch serving to intermittently start a motor or other power driven air-blast means for the purpose of forcing the rate of heat delivery. As applied to a coal fired hot-air furnace, the running fan motor induces circulation throughout the hot-air flues and simultaneously augments the ash pit draft to stimulate combustion of the fuel lying above the furnace grate. After the furnace temperature has been sufficiently raised, the blast fan is temporarily shut off, whereupon the hot air continues to circulate normally through the distribution ducts by gravity in the conventional manner.

My improved air distributing system includes an exteriorly disposed, auxiliary conduit which discharges into the ash pit and whose intake end is commanded by an automatically controlled induction tube that is periodically subjected to fan blast. Certain of my controls are preferably housed within this air tube and among such, is a thermostatically operated damper valve located contiguous to the fire box so as to come under the influence of its radiant heat and whereby the air draft under the grate is reduced when the fuel combustion tends to proceed at an abnormal rate. In series with said damper, there is compactly disposed a throttle valve having an actuating vane which holds the damper wide open while the air blast is potent, but allows the damper to move back into closed position whenever the motor fan ceases to function. The aforesaid furnace members are arranged to constitute a self-regulating draft control for the auxiliary air conduit that functions automatically in conformity with room heating needs.

As a further refinement, a pivotally mounted compensating valve is associated with the furnace stack, serving to automatically check the rate of combustion in the event the chimney draft should become excessive under erratic weather conditions. The present system further contemplates the modification of existing house heating furnaces by the use of simple, standardized attachments adapted to be readily applied without requiring extensive alterations in many prevailing types of hot-air furnaces. A time clock may be employed to set my air fan into operation between any desired day-time hours. All control appurtenances comprised in my system may be centralized in the furnace room to the end that

all distantly controlled draft adjusting chains, extended electric wiring and like extraneous adjuncts may be eliminated.

The object of my invention is to devise reliable and sensitive furnace appurtenances of the character indicated that shall promptly respond to relatively small room temperature changes without requiring frequent manipulative superintendence. In addition, the cited self-contained conduit together with its control features is made detachable as a unit to facilitate economical installation and otherwise promote a wide distribution on part of my improvements, all of which aspects will hereinafter be more explicitly pointed out.

Reference is had to the accompanying four sheets of drawings which are illustrative of a preferred structural embodiment of my invention, and in which drawings:

Fig. 1 schematically represents an elevational side-view taken in partial section of a furnace assembly equiped with my improved controls, while Fig. 2 shows a horizontal cross-sectional view thereof as taken along the broken line 2—2 of Fig. 1.

Fig. 3 is a cross-sectional view of my furnace arrangement as taken through the vertical plane 3—3 of Fig. 2; Fig. 4 shows a similar fragmental view as taken along line 4—4 of Fig. 2, while Fig. 5 further illustrates an enlarged detail of the sectioned portion of Fig. 1.

Fig. 6 represents a face view of a balanced chimney draft regulator that may be used in association with my other devices and Fig. 7 is a wiring diagram pertaining to my thermostatic motor controls.

Referring more specifically to the drawings, the structural embodiment of my controls as applied to a hot-air furnace will first be described. The more essential conventional elements thereof comprise a cylindrical shell or furnace jacket 10 containing the combustion space or fire box 11 equiped with a series of transversely disposed grate bars 13 and a fuel feed door 12 disposed at the front of the furnace. Underneath said grate lies the ash pit 14 forming a closed space that is confined between spaced side-walls 15 and the circular rear pit wall 16, which latter sets radially inward from the surrounding foot portion of the furnace shell 10. The free forward end of said side walls are preferably carried into engagement with the front of the shell and the pit given access through the customary ash door 17. When closed, the ash pit is intended to be

60

70

75

80

85

90

95

100

105

110

kept substantially air sealed except for egress upwardly through the grate bar passages.

The topmost portion of the fire box may be provided with a crownplate or superimposed header 18 having a flue outlet 19 that leads to the chimney 20. Said flue may be equipped with the usual manually operated throttle valve 21 and a draft check 22, although these supplementary draft controls do not represent essential components as applied to present purposes.

The jacket 10 spacedly encases the fire box and header in the customary manner to constitute an annular air heating chamber 23; extending outwardly from the uppermost crown region thereof are a series of hot-air outlet flues 24 which as shown in Fig. 1, connect with their respective discharge registers such as 25. As will be understood, one or more rooms lying above the floor 26 may each be provided with a floor register 27 which preferably feed into the common down-comer or the like means 28 to return the enervated room air in the flow direction indicated by arrows to the bottom housing section 29 or other similar collector duct means. The forward end of said housing may be adjoined to a rear shell opening that communicates freely with the reheating chamber 23 to constitute an extension thereof (see Fig. 2).

The present invention is more largely concerned with controls that are preferably centered in the vicinity of said collector duct. The illustrated box-like housing or elbow member comprises flat complementary side walls such as 30 together with a top wall 31 provided with a circular opening 32 into which the down-comer may be connected. The bottom wall 33 of said housing is shown apertured in alignment with the down-comer axis and a removable end cover 35 provides for access to the housing interior. A plurality of pivotally mounted fan blades 36 rotate about a common upright axis to command the wall opening 32 and these radially spaced blades are preferably given a considerable screw pitch so as not to unduly impede the rate of gravity air flow therethrough when this arises solely from small temperature differences. An electric motor 37 of the vertical type drives the fan and blows the air current axially downward and radially outward from the fan tips; the motor may be supported upon the stanchion 38 having a foot flange that rests directly upon the solid furnace foundation 39. Said stanchion is loosely entered through the bottom wall aperture out of direct contact therewith and closed with a suitable cushioning plate 40 arranged to afford a substantially noiseless fan motor mounting with the minimum of sound transmission to the adjacent metallic furnace ducts.

An adjustable thermostatic motor switch 41 may be placed in the down-comer near the discharge end thereof beneath the floor register 27 and made responsive to temperature changes occurring in the return air current. This thermostat may be of any suitable type but is preferably constructed with a spiral temperature responsive element adapted to adjustably oscillate a switch actuating spindle. As indicated in Fig. 1, this coiled element 41 may be disposed interiorly of the down-comer duct. Said switch may be of the mercurial bulb type tiltably carried by the spindle and protectively housed within the casing 41A. The operative tilt position of this bulb may be made adjustable and visible through a transparent casing cover, the disposition being such

that the bulb tilt may be altered from the outside of the casing without cover removal.

As disclosed in Fig. 2, I further provide for an auxiliary conduit 42 of which a medial region is preferably shaped to lie snugly around an exterior portion of the shell or jacket 10 and which conduit establishes communication between the interior of the housing 29 and the ash pit 14. Said arcuate conduit is so designed that it may readily be applied to certain existing furnaces and to this end, the pit terminal region of the conduit may be provided with a branch conduit 43 of which the innermost end is entered into the pit side wall 15, the jacket shell 10 for this purpose being apertured by a suitable cutter to closely pass said branch therethrough. The outermost free end of this branch may be flanged and provided with a cap 44 that is rotatably mounted for manipulation by a conveniently located handle 45. A cylindrical cock-like plug 46 of the truncated type may be attached to the cap and rotatably entered into the flanged mouth of the conduit. The conduit 42 discharges laterally into said branch conduit contiguous to its flange, the disposition being such that when the truncated plug is kept in its full-line position, the air-blast is allowed to freely enter the ash pit but when said plug is rotated through a full half-turn into its dotted position, this will wholly shut off the conduit 42 and prevent any dust from lodging in the heating chamber 23 while ashes are being removed from the pit 14. The branch conduit 43 is kept elevated to unobstructedly open into the ash pit near the door 17 for the reason that the accumulated ash tends to initially build up directly under the shaken grate and in the region of the rear wall 16, where it will not block the conduit discharge.

Attention will now be directed to the opposite or intake end of the conduit 42. This is extended to constitute the controlled induction tube 47 that may terminate in a detachable elbow having a horizontally disposed funnel 48 or other blast diverting means, which latter is cooperatively held in perimetrically embraced or radial relation with the tips of the rotating fan blades 36; while the motor is operating, a substantial volume of circulated air may thereby be bypassed and blown through the opened arcuate conduit. As will be obvious, the major portion of the fan blast will at the same time be directed into the heating chamber 23, which in turn accelerates the hot-air flow through the flues 24.

The tube 47 and adjoining end of said conduit may be interconnected by an elongated flange as at 49, the disposition of the described fluid conducting members being such that said tube assembly may as a unit be removably entered and sustained in place through a relatively small oblong hole cut into the side-wall 30 without dismantling the housing 29 or the upheld down-comer 28. Figs. 2 and 4 show the use of twin cooperative valves disposed in series within the confines of the control tube 47. Of these, the butterfly draft valve 50 is provided with a depending spindle 51 which carries a vane 52 adapted to be automatically opened when the fan blast blows thereagainst and thus throws the exteriorly disposed floating vane into its tilted position 52A. One movable tip of said valve is made to open counter to the air flow prevailing in the conduit 42 and the actuating vane is purposely placed in the path of the remaining major air flow portion so as to augment the opening effort exerted upon such substantially balanced draft valve.

A baffle plate 58 (see Fig. 5) may be resorted to for contracting and directing the air flow against the relatively small actuated vane. The spring 53 coiled around the spindle yieldably closes the last named valve while the fan blast is discontinued, thus automatically cutting off the air draft through the conduit leading into the ash pit and thereby bringing about a corresponding reduction in the rate of fuel combustion. When the fan is inoperative, the reduced air-flow impact becomes relatively small and fails to open the draft valve.

The companion control valve 54 may be similarly fulcrumed but in this instance, the depending trunnion 55 is shown equip with a supplementary thermostat 56 of the exteriorly disposed, spiral bimetal strip type of which the innermost end is operatively attached to said actuating trunnion while its outermost spiral end may be shiftably positioned through the medium of the adjusting screw 57. The spiral disposition is such that any augmented temperature acts to shut the valve 54. A stop pin 59 may be interposed between these closely spaced valves to prevent interference. This supplementary thermostat is also made responsive to the temperature of the collective room air returning to the furnace heating chamber through the down-comer 28. By manipulating the adjusting screw 57, the initial temperature at which the control valve 54 is intended to open, may readily be altered to meet the room heating requirements.

It is further emphasized that the thermostat 56 is purposely placed reasonably close to the exterior of the fire box 11 and subjected to the influence of radiant heat emanating therefrom. My auxiliary thermostat may be located within the furnace jacket confines or the interconnecting chamber end of the housing 29, thus exposing and subjecting this temperature responsive element to direct radiant heat, its contiguous disposition being such that an intervening body of air serves as a continuous, unobstructed heat conductive medium between the fire box and said element. Should the rate of fuel combustion at any time attain inordinate proportions, the thermostat 56 acts in the capacity of a safety device to dominate and automatically cut off the auxiliary ash pit draft, notwithstanding that the returning room air may not as yet have attained a temperature sufficient of itself to actuate either the thermostat 41 or the thermostat 56. It will be observed that the twin valve controls that command the conduit 42, serve to doubly protect the auxiliary draft that is allowed to enter the ash pit.

It now remains to describe my chimney draft adjunct shown in Figs. 2, 3 and 6. Located beneath the outlet flue 19 is a flanged framework 60 that is preferably inset into the chimney 20 as a substitute for the usual soot cleaning door. The rectangular opening of this frame is here controlled by a draft compensating or bypass valve 61 suspended upon the fulcrum shaft 62, which latter is shown disposed above the horizontal center line of the valve plate in such fashion that the valve normally tends to close of its own weight into its full-lined vertical position. The depending lower valve portion is additionally counter-weighted by a frictionally retained manipulative lever 63 adapted to be shifted away from the fulcrum axis and thereby adjustably alter the counterbalancing effect to suit draft needs. When said lever is thrown into its extreme lowermost position so as to overlap the

frame flange as shown by dotted outline in Fig. 6, the bypass valve becomes locked and inoperative. In its freed position, the valve plate 61 automatically opens inwardly to check any unforeseen excessive chimney draft resulting from windy weather or the like, the proper degree of valve tilt being governed by the lever position and thus preventing disturbances in the nicely balanced action of my induction tube.

The wiring diagram Fig. 7 shows a battery B or other source of electric current successively commanded by a switch S and a time clock C located near the thermostat switch 41 and the motor 37 wired in series therewith through the lead wires such as W₁ and W₂, it being preferred to utilize an electric clock that needs no periodic rewinding. When closing both the switch and clock, the control of the motor starting and stopping periods resides solely in my temperature responsive switch 41.

Assuming the furnace to be initially fired in the conventional manner and that heated air is being sent forth to the respective rooms, this will start normal gravity circulation of the heated air through the down-comer 28. The return air still being comparatively cool, the thermostatic switch 41 will complete the wiring circuit of Fig. 7 and start up the fan motor 37. The resulting air blast will cause the vane 52 to be rotated about the spindle 51 in a counter-clockwise direction as seen in Fig. 2 and thereby open the draft valve 50 in the control tube 47. Provided the fire box radiation has not yet reached prescribed limits, the supplementary thermostat 56 will gradually shift and regulate the control valve 54 into a position that is proportionate to the temperature prevailing in the down-comer and thus allow the desired quota of air-blast to flow through the conduit 42 into the ash pit. Assuming the ash pit door 17 to be kept closed, substantially the whole of such measured forced draft will then pass upwardly through the grate 13 to accelerate the rate of fuel combustion.

The resulting increase in furnace heat augments the temperature of the air circulating around the exterior of the fire-box wall 11 and gradually raises the hot air discharge through the flue 24 and the register 25, which in turn correspondingly augments the room temperature. The surplus of such warmed air may be repeatedly drawn into the down-comer 28 until the desired room temperature is attained. As a consequence, the thermostatic switch 41 is finally influenced to open the wiring circuit and shut down the motor 37 until such time that the down-comer temperature drops sufficiently to again restart the motor. When the motor ceases to operate, the floating vane will be turned clockwise by the spring 53 to shut off the butterfly valve 50 and thus prevent any of the circulated hot air from entering into the closed ash pit.

In the event that the fuel bed should become unduly forced by the fan blast and burn at an excessive rate, then the radiant fire-box heat will actuate the thermostat 56 and close the valve 54. The last named thermostat is made to supplement the action of the down-comer thermostatic switch 41 in case the latter should fail promptly to shut off the fan motor; that is to say, when the air blast temperature delivered through the conduit 42 exceeds predetermined limits, the thermostat 56 may close its valve 54 irrespective of whether the motor remains in operation or not. The adjusting screw 57 serves

80

85

90

95

100

115

120

125

130

135

140

145

150

to alter the point at which the thermostat 56 becomes effective.

As a further distinction, it is emphasized that my supplementary thermostat 56 holds the position of the cooperating valve 54 in accurate gravitational relationship to the heating requirements rather than in stepwise fashion or having to intermittently swing said valve between extreme full open and closed position such as obtains 10 when resorting to certain types of electric room thermostats.

The cooperating bypass valve 61 automatically opens under erratic draft conditions which might otherwise unfavorably affect the delicate 15 balance of my various furnace controls. Under inclement weather conditions, this compensating valve may be set to bypass at any predetermined degree of chimney draft. As regards the conventional flue throttle valve 21 and the draft 20 check 22, these need not be resorted to while my controls are kept in proper working order. As will be understood, the time clock C opens the wiring circuit between certain periods, especially during night hours, whereupon the furnace continues 25 to operate normally without air blast at a relatively light firing rate. When however the clock reestablishes the circuit, the fan motor will again be placed in service and thus promptly bring the respective rooms up to the desired 30 raised temperature for which the controls may have been set.

While the previous description has been primarily directed to a hot air furnace burning solid fuel, it will be apparent that similar underlying regulating features find application to oil and gas fired furnaces. My simple control appurtenances are further applicable to both new or old furnace equipment and can be installed upon the latter at low first cost by the average 40 householder without need of special tools or exceptional skill. In addition, it is not essential that all the described devices be introduced in one and the same furnace; as an instance, the valve controls associated with the conduit 45 may be separately utilized without fan cooperation. This disposition is particularly appropriate where the down-comer is connected to take cold air supply from the outside atmosphere rather than from any one of the rooms. On the other 50 hand, where no blast motor is employed, the remaining thermostatically controlled valve 54 may still be utilized to regulate the ash pit draft. The use of my double thermostats however insures a more accurate averaged control for all the 55 flue interconnected rooms which can thereby be held to within a few degrees of a common predetermined temperature. Any of the individual room registers may be shut off without interfering with the proper operation of my furnace 60 devices. If desired, the hub of the vane 52 may be loosely fitted to its spindle and adjustably fastened together by the set screw 51A (see Fig. 4) to allow of shifting the angularity between the 65 throttle valve 50 and its actuating vane; by this means, the degree of valve opening for any given blast pressure may be altered within reasonable limits.

All the described controls may be compactly located within the confines of the furnace room, 70 As disclosed in Fig. 1, this result is attained by making the thermostatic action dependent upon the return temperatures prevailing in the down-comer 28 without need of individual room thermostats. The described thermostat adjustments 75 are intended to be so set that the blast fan is

shut down when the respective heated rooms assume the desired comfortable temperature, after which the normal gravity circulation of the heated furnace air is resumed. It is believed that the foregoing description when read in connection with the accompanying drawings makes apparent the intended construction, operation, and advantages of my improvements; it being understood that their more outstanding features are subject to considerable latitude in practical application, and that various modifications may be resorted to, all without departing from the spirit and scope of my invention as defined in the appended claims.

I claim:

1. In a heating system, the combination of a fire box having an ash pit and heating chamber associated therewith, a duct conveying air of variable temperature to the heating chamber, induction tube means serving to divert a portion of said air into said tube for delivery to the ash pit, and a thermostatically actuated valve controlling the flow of diverted air, said valve being automatically actuated in response to variations occurring in the air temperature.

2. In a hot air furnace system comprising a jacket, a fire box, an ash pit and a heating chamber, the combination of down-comer means conveying air to the heating chamber, duct means interposed between the down-comer and said chamber, an auxiliary conduit having one of its ends entered into said duct and of which conduit a medial portion extends exteriorly of the jacket to bypass air from the duct for delivery into said pit, and a thermostatically actuated valve commanding the air flow through said conduit, the thermostatic element of said valve being subjected to radiation emanating from said box.

3. A hot air furnace system comprising an apertured jacket enclosing a heating chamber and an ash pit including a pit side-wall having a hole therethrough in substantial alignment with the jacket aperture, tubiform housing means serving to convey air to the heating chamber, a branch conduit entered through the jacket aperture and said side-wall hole, an induction tube extending within the housing means and arranged to divert a portion of said air therethrough, an auxiliary conduit disposed exteriorly of the jacket and interconnecting said tube with the branch conduit, and thermostatically actuated valve means controlling the air flow through said auxiliary conduit.

4. A hot air furnace system comprising an ash pit, a heating chamber, duct means conveying air to the heating chamber, a power driven blast fan arranged to accelerate air circulation through said duct, means for intermittently starting said fan, an induction tube cooperating with said fan to divert a minor portion of said air circulation through the tube, conduit means interconnecting the tube with the ash pit, a draft valve of the butterfly type disposed interiorly of the conduit, and a floating vane disposed exteriorly of the conduit and operatively connected to the draft valve, said vane being actuated by a remaining portion of the fan blast.

5. A hot air furnace system comprising an ash pit, a heating chamber, duct means conveying air of variable temperature to the heating chamber, induction tube means arranged to divert a portion of the air flowing into the duct and deliver the diverted air into the ash pit, a control valve mounted to command the flow of said diverted air, and a thermostat disposed in the air

80

- flow path and serving to gradationally regulate said valve in proportionate relation to the aforesaid temperature variations.
6. A hot air furnace system comprising an ash pit, a heating chamber, duct means conveying air of variable temperature to the heating chamber, said duct including a wall aperture, a power driven blast fan disposed within the duct and serving to accelerate air circulation therethrough, induction tube means including a control valve provided with an actuating trunnion, said tube being detachably mounted through the wall aperture and placed into cooperative relation with the fan to divert a portion of the circulated air through said tube for delivery into the ash pit, an elongated thermostat of which one end portion is operatively attached to said trunnion and the opposite end of which thermostat is shiftably disposed, and adjusting screw means serving to alter the position of said shiftable thermostat end.
7. A hot air furnace system comprising an ash pit, a heating chamber, a room register, down-comer means returning enervated air of variable temperature from the register to the heating chamber, duct means interposed between the down-comer and the heating chamber, an electric motor driven fan means serving to accelerate the flow of returned air, an automatically controlled induction tube means cooperating with said fan to divert a part of the returning air into said tube for delivery into the ash pit, a thermostatically actuated switch of which the thermostatic element is made responsive to temperature variations in the aforesaid returning air, a source of motor current, and lead wires operatively interconnecting the current source with said switch and the motor.
8. A furnace system comprising an ash pit and a heating chamber, duct means conveying air to the heating chamber, induction tube means arranged to divert for delivery into the ash pit a portion of the air flowing into said duct, a pair of closely spaced throttle valves of the butterfly type commanding the flow of air through said tube, and interposed stop means limiting the opening of the respective valves and preventing interference therewith.
9. A furnace system comprising an ash pit and a heating chamber, down-comer means conveying a supply of air of variable temperature to the heating chamber, tubiform housing means interposed between the down-comer and said chamber, a motor driven blast fan serving to stimulate air circulation through said housing, switch means for intermittently starting said fan, said switch being thermostatically controlled and made responsive to temperature changes in the conveyed air, and induction tube means arranged to divert for delivery into the ash pit a portion of the air flowing into said housing, said tube be-
- ing provided with a pair of automatic valves of which one is thermostatically controlled and the other actuated by the fan blast.
10. A hot air furnace comprising fire box means encased within a jacket to provide for a heating chamber therebetween and which chamber is supplied with air by duct means arranged to constitute a continuation of said chamber, an outlet flue for said chamber, conduit means diverting a portion of such air supply to the fire box, and control means commanding the air flow through said conduit, said means including a thermostat located within the aforesaid chamber in a directly responsive relation to the radiant heat emanating from the fire box and serving to arrest air flow when the fire box reaches a predetermined temperature.
11. A hot air furnace comprising a heating chamber, an ash pit, tubular housing means conveying air to the heating chamber, a fan of the rotating spiral bladed type mounted within the housing to turn about an upright axis and serving to accelerate the flow of said air, and an open ended conduit communicating with said housing to divert a portion of said conveyed air to the ash pit, the receiving end of said conduit being cooperatively disposed in a closely contiguous perimetric relation to the blade tip region of said fan and arranged to conduct air from said region in a direction radially outward from the aforesaid vertical fan axis.
12. A hot air furnace comprising an ash pit, a jacketed heating chamber, duct means conveying air to the heating chamber and which duct includes a wall aperture, a power driven blast fan disposed within the duct to accelerate the air circulation therethrough, valve controlled induction tube means removably inserted through the wall aperture and placed in a cooperative relation with the fan to divert a portion of the circulated air through said tube, and a conduit disposed exteriorly of the heating chamber jacket and of which conduit one end is detachably secured to the delivery end of said tube and the other conduit end placed in communication with the ash pit, said tube being kept accessible and demountable without removal of the duct means.
13. In a heating system, a furnace including a warm air duct, means for producing a forced draft for said warm air duct, and thermostatically controlled means for diverting a portion of the forced draft to the furnace to increase the rate of combustion.
14. In a heating system, a furnace including a warm air duct, means for producing a forced draft for said warm air duct, a thermostat responsive to the heat produced by said furnace, and means controlled by said thermostat for diverting a portion of the forced draft to the furnace to increase the rate of combustion.

GEORGE W. BAILEY.
